United States Patent Office

Des. 203,923
Patented Feb. 22, 1966

203,923

CHAIN SAW

Richard K. Whitehead, Sr., Richard K. Whitehead, Jr.,
Alvin C. Whitehead, and Harry C. Whitehead, all of
1202 Zonolite Road NE., Atlanta, Ga.

Filed Apr. 13, 1965, Ser. No. 84,764

Term of patent 14 years

(Cl. D93—3)

FIG. 1

FIG. 2

FIG. 3

FIG.4

FIG.5

FIG.6

FIG. 1 is a side elevational view of a chain saw showing our new design;

FIG. 2 is an elevational view of the opposite side thereof;

FIG. 3 is a front elevational view thereof;

FIG. 4 is a rear elevational view thereof;

FIG. 5 is a top plan view thereof; and,

FIG. 6 is a bottom plan view thereof.

The dominant features of our design reside in the portions shown in full lines.

We claim:

The ornamental design for a chain saw, substantially as shown and described.
